UNITED STATES PATENT OFFICE.

JOSEPH M. MERROW, OF HARTFORD, CONNECTICUT, ASSIGNOR TO THE MERROW MACHINE COMPANY, OF HARTFORD, CONNECTICUT, A CORPORATION OF CONNECTICUT.

SEWING-MACHINE.

1,278,973.

Specification of Letters Patent. Patented Sept. 17, 1918.

Application filed September 18, 1916. Serial No. 120,829.

To all whom it may concern:

Be it known that I, JOSEPH M. MERROW, a citizen of the United States, residing in the city of Hartford, county of Hartford, State of Connecticut, have invented certain new and useful Improvements in Sewing-Machines; and I do declare the following to be a full, clear, and exact description of the same, reference being had to the accompanying drawings, forming a part of this specification, and to the characters of reference marked thereon.

This invention relates to lubricating means for sewing machines. Certain machines of this class are characterized by looper mechanisms, of which, as is well known in this art, extremely high speeds are required. In the operation of such machines, increased efficiency naturally obtains by supplying continuously, adequate lubrication, directly to the relatively movable surfaces which are subjected to the greatest amount of frictional resistance. The provision of novel devices for carrying into effect this desideratum is one object of the present invention.

A design typical of the Merrow overseaming machine such as that illustrated in application for U. S. patent Serial No. 876,917, filed December 12, 1914, includes in its make-up a removable frame cap upon which is movably mounted looper mechanism such as that of which mention has been made above. It is a further object of the present invention to make provision in said frame cap for a lubricant reservoir with ducts and leaders associated therewith in such a manner that said frame cap together with the looper mechanism and its complete lubricating system may be assembled independently of the rest of the machine, and removed from the machine as an entirety to permit inspection and adjustment of the parts sustained thereby.

These and other objects which will hereinafter appear are identical with those of an invention forming the subject matter of an application filed by me May 19, 1915, and bearing Serial Number 29,231, now Patent No. 1,217,976, dated Mar. 6, 1917. The means for attaining these objects, however, is simplified in the construction disclosed in the accompanying drawings, described in the following specification, and defined in the appended claims.

In the drawings,—

Figure 1 is a front view in elevation of a Merrow overseaming machine equipped with the devices which comprise the present improvements.

Fig. 2 is an inner face view of a removable frame cap of the machine shown in Fig. 1.

Fig. 3 is a sectional view on line 3—3 of Fig. 2.

Fig. 4 is a detail sectional view on line 4—4 of Fig. 2, and Fig. 5 is a detail view hereinafter more fully described.

Similar characters of reference designate corresponding parts throughout the several views of the drawings in which it will be noted that Fig. 1 is drawn to a somewhat smaller scale than the other views.

Referring to said drawings the numeral 2 designates the frame of the machine, 3 the head, 4 the presser foot and 5 the needle or work plate. An eye pointed needle 6, operable to move in a path extending above and below the needle plate 5, cooperates with the loopers 7 and 8, which are operatively supported on the frame cap 9, all as will hereinafter be more fully described. Said frame cap 9, which is secured to the machine frame at top and bottom by the screws 10, forms for an opening or cavity 11 in the machine frame, a closure or cover plate. Cam cylinders 12 and 13, housed within the cavity 11 are secured respectively to the shafts 14 and 15, the former shaft extending through to the rear of the machine frame where it is provided with a combined hand wheel and driving pulley 16. Intermeshing gears 17 and 18 are associated with the respective cam cylinders 12 and 13 so that when the pulley 16 is rotated the shafts 14 and 15 will, together with said cam cylinders, rotate in unison.

The function of these cam cylinders is to actuate the loopers 7 and 8 and a driving relation between the cylinders and said loopers may be established in a manner which will now be described. The lower cam cylinder 12, is provided with two cam grooves 19 and 20, while the upper cam cylinder 13 is provided with a cam groove 21. Extending respectively from oppositely disposed arms 22 and 23 of a carrier 24 for upper looper 7, into the respective cam grooves 19 and 21, are studs 25 and 26, provided with anti-friction rolls 27 and 28 re-

spectively. Similarly a driving relation between lower looper 8 and cam cylinder 12 involves the carrier 29 from which there extends into groove 20 of cam cylinder 12, 5 a stud 30 provided with an anti-friction roll 31. By virtue of these driving connections the loopers 7 and 8 may be suitably moved in a manner well known to those familiar with this art, to coöperate with each other 10 and with the needle 6, the latter being driven in any convenient way as from the shaft 15, through the parts indicated in a general way by 32.

The peculiar motion imparted to the 15 looper carrier 24 by the correlated cam grooves 19 and 21 is accommodated preferably by providing a movable support for said carrier. This support may vary as to character, but as shown, it comprises a slide 20 or block 33 mounted for reciprocatory movement on the inner face of the frame cap 9, between guides 34 and 35, the latter guide being movable to take up wear and backed up by an adjusting wedge 36 which bears 25 against the shoulder 37 of said frame cap 9. In addition to the bodily movement of looper carrier 24, permitted by the slide 33 provision is also made for an oscillatory movement thereof, involving a pivotal connection comprising, as shown, a trunnion 38, 30 projecting from said carrier 24, intermediate the oppositely disposed arms thereof, and journaled in said block 33. In order to retain the carrier 24 in its proper pivotal 35 relation to the supporting block 33 and to provide additional support for said carrier, a guide bar 39 is mounted on the frame cap with a bearing surface 40, effectively positioned for the purposes stated. Said 40 guide bar is provided at one end with an offset foot 41 countersunk to receive a screw 42, tapped into the frame cap, while at its opposite end said bar has a foot block 43 extending between the guides 34 and 35, 45 which block is bored to receive a screw 44 countersunk in the front or outer face of the frame cap, and tapped into the bar proper.

The movement required of the lower 50 looper 8, in this case, is an oscillatory one, by reason of which the looper carrier 29 may have a simple pivotal support. Such a support is provided in the taper stud 45 which is tapped into the frame cap and furnished with a securing nut 46.

The embodiment of the present invention within and applied to the devices hereinabove generally described will now be pointed out and explained.

60 In the upper part of the frame cap 9, which is somewhat enlarged for the purpose, is provided a lubricant reservoir comprising in the present case a pair of drilled holes 47 and 48, plugged at the entering ends thereof and connected by the bore 49. A duct 50,

leading from bore 49, communicates with a depending plate 51, suitably secured to the frame cap and provided with a perforation 52, which forms a delivery opening from the duct, through which lubricant can 70 flow to the inclined outer face 53, of said plate 51. From a point below the delivery opening 52, the lower part of plate 51, diverges in two edges 54 and 55, toward two points or fins 56 and 57, so that lubricant 75 issuing from said delivery opening will flow along said edges to both of said fins. The fin 56, depends into adjacency to a path traversed by the looper carrier arm 23, which supports stud 26 and roll 28. Due to 80 this arrangement lubricant applied to fin 56 will accumulate at the point thereof drop by drop, and as arm 23 passes, be wiped into notch 58 where it is available for the bearing surfaces for which it is intended. 85 The fin 57 depends over, and is adapted to deliver lubricant received thereby into, a groove 59 in the guide bar 39. From the bottom of this groove, which is somewhat downwardly inclined from its open end, a 90 duct 60 leads to a plate 61, the latter being perforated as at 62 and secured to the guide bar with said perforation in register with the duct so that lubricant may be delivered therethrough to the outer inclined face of 95 the plate. Like the lower part of plate 51, that of plate 61 from a point below perforation 62, diverges in two edges 64 and 65 to form two fins 66 and 67, which respectively depend into adjacency with paths traversed 100 by arm 22 and carrier 29, whereby in a manner similar to that in which lubricant is delivered from fin 56 to roll 28, lubricant will also be delivered respectively by fins 66 and 67 to rolls 27 and 31. 105

From the foregoing statements it will be apparent that the fin 56 of upper plate 51 delivers lubricant to one cam roll, and that fin 57 of said upper plate conveys lubricant which is subsequently divided by 110 the lower plate 61 and delivered to two cam rolls. It follows therefore, other factors being equal, that less lubricant should be conducted to fin 56 than to fin 57. Preferably for the purpose of securing the required 115 division of lubricant between fins 56 and 57, delivery opening 52, is located more on one side than on the other of a plane extending vertically through the point from which the lower part of depending plate 51 diverges 120 in the two edges toward the respective fins. In this manner a very small stream or supply of oil may be divided into unequal parts. See diagram Fig. 5, in which the path of the flow of lubricant is indicated by dotted lines. The width of this path is divided by the point of a notch formed by the re-entering edges 54 and 55, the division as shown, being in the ratio of two to one, by virtue of which one third of the flow of 130

lubricant is directed to one fin and two thirds to the other fin. By varying the ratio mentioned any desired division of the lubricant may be obtained.

- 5 Means for controlling the flow of lubricant from the reservoir may comprise a needle valve as 68, tapped into the frame cap and provided with a head 69, by means of which it may be manipulated to move 10 it toward and from the valve seat 70 at the entrance of duct 50. The head 69 is provided with an indicator as the mark 71 to visibly disclose whether the valve is open or closed.
- 15 In the front face of the frame cap 9 and communicating with the reservoir is a tapped hole 72, countersunk to receive the head 73 of a threaded bushing 74. Said bushing has a sight opening 75, and is countersunk from its inner end to receive the transparent disk 76, washer 77 and spacing ring 78. The latter is adapted to bear against a second washer 79, at the bottom of the tapped hole thus providing for tight 25 joints between the several parts mentioned when the bushing is screwed into place, to provide means whereby an operator can readily see if the reservoir contains sufficient lubricant. Ports through which 30 lubricant may be introduced into the reservoir are designated by 80, and these may also serve as air vents to permit the lubricant to flow freely.

Having thus described my invention, what 35 I claim as new and desire to protect by Letters Patent is,—

1. In a sewing machine, in combination, a pair of loopers, a carrier for each looper, means including projections on the looper 40 carriers for actuating the loopers and a pair of lubricant conveying plates, each plate having one or more depending fins to convey lubricant to respective projections on the looper carriers and one of the plates 45 having a depending fin to convey lubricant to the other plate.

2. In a sewing machine, in combination, a plurality of loopers, a carrier for each looper, means including projections on the 50 looper carriers for actuating the loopers, a plate having depending fins to convey lubri-

cant toward the projections on the looper carriers, and means for delivering different amounts of lubricant to respective fins.

3. In a sewing machine, in combination, 55 a plurality of loopers, a carrier for each looper, means including projections on the looper carriers for actuating the loopers, a support, a guide bar for one of the carriers, secured to the support and lubricant 60 conveying plates secured respectively to the support and to the guide bar, the plate secured to the support having depending fins to respectively convey lubricant toward one of the looper carrier projections and toward 65 a duct in the guide bar, and the plate secured to the guide bar having depending fins to respectively convey lubricant to projections on the looper carriers.

4. In a sewing machine, a lubricant conveyor comprising a depending plate having a lower edge thereof interrupted by a notch, and means for causing lubricant to flow upon the plate in a path whose width is unequally divided by the apex of the notch. 70

5. In a sewing machine, in combination, a frame cap having a reservoir therein for containing lubricant, a pair of loopers movably supported by the frame cap, projections associated with the loopers by which the 80 loopers may be actuated, a pair of lubricant conveying plates, each plate having one or more depending fins to convey lubricant to respective projections associated with the loopers, one of the plates having a depending fin to convey lubricant to the other plate, and a needle valve for controlling the 85 flow of lubricant from the reservoir to one of the plates.

6. In a sewing machine, a lubricant conveyor comprising a depending plate having a lower edge thereof interrupted by a notch, said plate also having for the passage of lubricant an opening so located with respect to the notch that the path followed by lubricant issuing from the opening will be unequally divided by the apex of the notch. 90 95
